UNITED STATES PATENT OFFICE

MAXIMILIAN VOGLMAYER, OF VIENNA, AUSTRIA

METHOD OF FOLDING, CLOSING, AND OPENING LETTERS RENDERED INACCESSIBLE
WITHOUT ENVELOPES

Application filed December 16, 1927, Serial No. 240,605, and in Austria October 22, 1927.

The usual business-method of closing letters for despatch is to fold the sheet cross-wise and put it in an envelope with a gummed-flap which is moistened and stuck down. The usual method of opening business-letters is to cut open the envelope, take out the letter-sheet, unfold and stamp the same with the dates of receipt. Both methods being carried out manually.

The object of my invention is to spare manual work in despatch and receipt of letters, to reduce their weight and volume, to render inaccessible the contents and to promote the standardization of the letters.

My invention consists in a novel shape of the closed letters, an improved disposition of the parts of the contents and in a new method of folding and closing, as well as opening and unfolding such letters and providing the same with the stamp of receipt.

Figs. 1 to 6 of the drawings show the letter-sheet in the different stages of the new method.

The letter-sheet (Fig. 1) is divided into four areas A, B, C, D by three parallel folds. The topmost area A contains a space E and a space F for the names and addresses of the sender and of the addressee respectively, this area being the heading of the letter. The adjacent area B contains a space G for business-remarks, such as telephone number, cable-address, bankers, codes and C. The space H is reserved for the stamp of receipt (Fig. 6), while the interrupted line J serves for writing the relating- and register-remarks and the dates of despatch. The ruled space K of the areas C and D is reserved for the communications or the letter-text.

The sheet is folded by bending the area D inwards so as to cover the area C, now the area B is folded inwards and the area A outward and serves as postal-address (Fig. 2), thereby covering practically the half of the front-side of the closed letter. The remaining half L of the front side is reserved for the application of postage-stamps and other signs of postal-service. This space L is situated below the postal-address if the sizes of the areas A and B are nearly equal, but less than the sizes of C and D. If the division

is altered, so that the sizes of the areas B, C and D are nearly equal and only the size of the area A is smaller, the space L will be situated above the postal-address, as shown in Fig. 4. This figure shows on the left side 55 how the lateral borders are superposed.

The folded letter is closed (Fig. 3) by notching the open lateral borders by means of oppositely acting coggings. The notches at the front-side of the letter, in the drawing represented by short lines, correspond to the spaces between the notches at the back-side.

Fig. 5 shows a received letter with severed borders.

Fig. 6 illustrates the letter-sheet unfolded and stretched, applied with the stamp of receipt and perforated for filing into a register.

Letter-enclosures are wrapped horizontally into a protecting-sheet, to be inserted between the areas C and D when folding the letter, and secured by notching simultaneously the lateral superposed borders of the protecting-sheet together with those of the 75 letter-sheet.

In contrast with a gummed closure which can easily be opened and closed again without a mark of tampering, the notched closure of a letter according to the present method 80 would irretrievably be destroyed at an attempt upon the contents of the folded areas C and D by lifting their overlapping area B, the width of which being in a limited proportion to the distance between the rows of 85 notchings sufficient to tear the perforated paper at a certain angle of elevation. Therefore the security of the contents is increased, although the letter is not secured between the notching rows for the purpose to be opened 90 merely by detaching the notched borders.

I claim:—

1. Method of folding and closing letters without the use of an envelope and whereby the letter-head used as a postal address is 95 turned outward which consists in transversely folding a letter sheet into individual areas by first folding the lower area to cover the middle area and in this manner concealing the communication upon their face, folding ,

- inwardly the upper area which contains the address, business remarks, date of despatch and a free space for the stamp of receipt reversely folding the outer portion of the upper area upon itself so as to expose the address and leaving free a part of the underside of the letter sheet for the application of postage stamps and post marks, and finally closing the lateral superposed borders of the letter sheet by opposite interlocking notchings.
- 10 2. The method of folding and closing letters without an envelope which consists in folding the lower portion of a letter sheet inwardly upon itself to the form of an envelope size, then folding the top portion of the sheet upon the first folded area, then reversely folding the outermost portion of the top part of the sheet upon itself, said latter portion carrying the address and leaving free a part of the underside of the letter sheet for postage stamps and post marks, and finally closing the lateral interlocking borders of each side by a layer of superposed notchings.
- 15 3. The method of folding, closing and opening letters without an envelope which consists in folding a letter sheet horizontally into four areas by first folding the lower two-thirds of the sheet upon itself, overlapping the first folded areas by the remaining part of the sheet, reversely folding the outer portion of the last mentioned overlapping part upon itself so as to cover the upper one-half front of the folded letter thereby providing an address and stamp receiving face, closing the lateral superposed borders of each side of the sheet by a row of interlocking notchings, the width of said overlapping part being limited by a due proportion to the distance between the rows of notchings, and finally opening such letters by separating the notched borders.
- 20 4. The method of folding and closing letters without an envelope which consists in folding the lower portion of a letter sheet horizontally upon itself, folding the uppermost portion of the sheet upon the folded lower areas and reversely folding the outermost portion of the upper part of the sheet upon itself and leaving free a sufficient part of the underside of the letter sheet for the application of postage stamps and borders of each side of the folded sheet by a row of interlocking notchings.
- 25 5. A method of folding and closing letters as claimed in claim 1, consisting in the arranging of a protecting sheet between the folded lower two-thirds of the letter sheet wrapping an enclosure horizontally and notching the lateral superposed borders of the protecting sheet together with those of the letter sheet substantially as and for the purpose set forth.
- 30 6. A method as claimed in claim 3, consisting in applying a protecting sheet for enclosures within the folded lower two-thirds

of the letter sheet wrapping the enclosure by at least one fold which lies beneath the fold of the letter sheet formed when overlapping its first folded areas, and notching the lateral superposed borders of the protecting sheet together with those of the letter sheet whereby when opening the letter the protecting sheet will be severed, substantially as and for the purposes set forth.

In testimony whereof I affix my signature.
MAXIMILIAN VOGLMAYER.
